UNITED STATES PATENT OFFICE.

JOHN PETTY, OF LEBANON, PENNSYLVANIA, ASSIGNOR TO JO PET, INC., OF LEBANON, PENNSYLVANIA, A CORPORATION OF PENNSYLVANIA.

SOOT BLOWER.

Application filed May 19, 1923. Serial No. 640,189.

My invention relates to soot blowers especially designed for use in connection with fire tube boilers in which the tube groups are separated by vertical spaces. The object of my invention is to provide a soot blower of simple and efficient construction whereby the different tube groups or sections of the tube groups can be separately blown to clear out the soot and whereby the soot blowing devices can be swung away from the tubes in sections when, for any reason, it is desirable to get at the tubes.

The nature of my improvements will be best understood as described in connection with the drawings in which they are illustrated and in which

Figure 1 is a front elevation of a fire tube boiler provided with my improved soot blowing apparatus.

Figure 2 is a plan view of the end of the boiler and the soot blowing apparatus, as shown in Fig. 1.

Figure 3 is a side elevation of the apparatus.

Figure 4 shows partly in section a detail of construction.

Figure 5 is a sectional detail on the line 5—5 of Fig. 4.

Figure 6, a perspective shown detail of construction.

Figure 7, a perspective sectional view of one of the nozzles, and

Figures 8 and 9, respectively, front elevations showing modifications in the construction of my soot blowing apparatus adapted for different constructions of boilers.

A indicates the boiler which, as shown in Fig. 1, has three separate tube groups, the first consisting of three vertical rows of tubes indicated at B, B', B''. The second or central group is made of seven vertical rows of tubes, indicated at C, C', C'', C'', C'', C'' and C'', while the third group of tubes is made up of three vertical rows indicated at D, D', D''. The vertical spaces indicated between the tube groups are indicated at b, c.

E indicates a steam conduit having branches indicated at E' and e'. The branch E' connects with two conduits indicated at E'' and F. The conduit E'' is continued, as indicated, at E'', E'', E'' and E'' and terminates in an upwardly extending vertical portion E'' in which is rotatably secured the steam conduit indicated at I. The upper end of this conduit, see Fig. 4, is closed by a plug I'

above which is formed a tubular seat I''. I'' is a steam pipe extending out horizontally from the rotatable steam conduit I to the inner face of which, and preferably, as shown, so as to extend inward from the conduit I'', are secured the series of steam conduits I' arranged so as to register with the vertical tube rows B, B', B'', and from which extend steam nozzles J located so as to register with the individual tubes of these rows. The pipe system described constitutes a soot blower frame and such a frame may obviously be made up of different arrangements of connected pipes.

The branch F extending from the steam pipe E' is continued, as indicated, at F', F'' and F''' and connects with the vertical conduit K which lies in between the rotatable pipe I and the head of the boiler and terminates in a return bend K' in which is rotatably secured the conduit L which is also rotatably supported on the thimble L'' secured in the socket I'' of the conduit I and provided with a block indicated at L''. From the rotatable conduit L extends the horizontal conduit L''' to which is secured a series of vertical conduits L'', L'', arranged to register with certain tube rows of the intermediate bank of tubes and provided with nozzles J which register with the individual tubes.

At the right hand side of the construction shown in Fig. 1 I have shown a conduit e' leading from the pipe E and connecting with branches f and e'' shaped and continued like the conduits shown at E'' and F and connecting with similar rotatable conduits I and L. At G and G' I have indicated valves at the junction of the branches by which steam can be turned into the conduit I or conduit L at will or shut off from both of them. At M I have indicated a bracket for properly spacing and supporting the rotatable conduit I and the conduit K, and at M' I have shown a bracket secured to the reverse coupling K' at the head of the pipes K.

O, O, etc. indicate brackets extending out from the soot blower pipes, grooved to receive a rod P which, when in place, holds the different independently movable parts of the soot blowing apparatus in position.

The operation of my device is, of course, obvious. Steam can be turned into any of the different separate parts of the soot blowing system at will and when it is desired to

get at any group of tubes it is only necessary to remove the locking bar l' to enable either the rotatable conduit I or L with its attached parts to be turned and the soot blowing mechanism attached to it, turned back, as indicated, for instance, in dotted lines, Fig. 2.

In the construction shown in Fig. 8, my device is adapted for a boiler having two tube groups separated by a wide space so that two sets of rotatable vertical aligned conduits, indicated at i and l , can be used. Independent steam pipes E , E^6 and F , F^3 , are here shown as supplying the upper and lower conduits. The horizontal conduits are indicated at l^3 and the vertical conduits at l^4 .

In Fig. 9, a modification is shown in which my device is adapted for use with a boiler having four separate groups of tubes.

Having now described my invention, what I claim as new and desire to secure by Letters Patent, is:

1. In combination with a fire tube boiler having tube groups separated by vertical spaces, a soot blower construction comprising rotatable steam conduits arranged opposite to the vertical spaces between the tube groups, tubular soot blower frames connected to each rotatable conduit and steam nozzles connected to said frames spaced to register with the tubes of the respective tube groups when in operative position.

2. In combination with a fire tube boiler having tube groups separated by vertical

spaces, a soot blower construction comprising pairs of independently rotatable vertically aligned steam pipes opposite to the vertical spaces between the tube groups, tubular soot blower frames connected to each rotatable pipe having nozzles arranged to register with the tubes of the respective groups of tubes when the frames are in operative positions and means whereby steam can be admitted at will to any one of the vertical rotatable pipes.

3. In combination with a fire tube boiler having tube groups separated by vertical spaces, a soot blower construction comprising pairs of independently rotatable vertically aligned steam pipes opposite to the vertical spaces between the tube groups, tubular soot blower frames connected to the respective rotatable pipes and stem nozzles secured in the tubular frames to register with the tubes, vertical steam supply pipes connected to the upper rotatable pipes and extending down between the rotatable pipes and the boiler head, a steam supply pipe connected to the bottom of each lower rotatable pipe, means connecting the respective supply pipes of each pair of rotatable pipes, a main supply pipe connected to said means, and a valve in each of said means arranged to permit steam to be admitted to either of the respective supply pipes at will.

JOHN PETTY.
